UNITED STATES PATENT OFFICE.

DOUGLAS S. CAMPBELL, OF CLEVELAND, OHIO, ASSIGNOR TO THE POCOHONTAS OIL COMPANY, OF CLEVELAND, OHIO, A CORPORATION OF OHIO.

DESIGN FOR A SIGN.

Application filed June 11, 1923. Serial No. 6,455. Term of patent 3½ years.

To all whom it may concern:

Be it known that I, DOUGLAS S. CAMPBELL, a citizen of the United States, residing at Cleveland, in the county of Cuyahoga and State of Ohio, have invented a new, original, and ornamental Design for a Sign, of which the following is a specification, reference being had to the accompanying drawing, forming part thereof.

The figure is a perspective view of a sign

showing my new design. The sign is used for gasoline filling stations. It has opposite side faces which are alike and are spaced apart as indicated by the drawing, the two faces and the spacers therebetween being united to form a single structure.

I claim:

The ornamental design for a sign, as shown and described.

DOUGLAS S. CAMPBELL.
